UNITED STATES PATENT OFFICE.

LEAVITT HUNT, OF WEATHERSFIELD, VERMONT.

IMPROVEMENT IN PLOWS.

Specification forming part of Letters Patent No. 93,994, dated August 24, 1869.

To all whom it may concern:

Be it known that I, LEAVITT HUNT, of Weathersfield, in the county of Windsor and State of Vermont, have invented certain new and useful Improvements in Plows; and the following is hereby declared to be a full, clear, and exact description of the same, reference being had to the accompanying drawings.

My invention relates principally to what are known as sulky-plows, although a portion of it is designed for use with any plow of ordinary or suitable construction.

In Letters Patent No. 77,617, dated May 5, 1868, I have described a sulky-plow in which the plow-beam is connected with the whiffletree, and is combined with an auxiliary beam hinged to the axle, and actuated by a lever so as to raise or depress the plow, the depth of penetration of the latter being regulated by a gage, and both the plow-beam and the frame or pole to which the whiffletree is secured being slotted, so as to allow the plow the necessary longitudinal play while being raised or lowered.

The plow to which my present invention relates is organized upon the same general plan as that just stated, but contains many features of importance and utility which are not shown in the patented plow referred to.

My invention may be stated to consist, first, in the combination, substantially as hereinafter described, with the hinged plow-beam and sulky-frame, of a stiff or rigid gage-bar to regulate the depth of furrow, and to cause the plow-point to bite or enter the ground at once; second, in the combination, with the plow-beam, of arms hinged to the sulky-frame, and connected with the beam and with the lever for elevating the same, as hereinafter described, so that said arms shall serve both to stiffen or brace, and, in connection with the lever, to raise or depress, the plow; third, in the combination, with the slotted plow-beam and whiffletree held in a slot in the sulky-frame or pole, and connected with the beam by a draft-chain or equivalent device, of the hinged bracing-arms, the lever for actuating the same, and the rigid or stiff gage-bar; fourth, in the combination of the plow-beam with the hand-lever for raising or lowering the same, and an auxiliary foot-lever, also connected with the beam, and adapted to act in conjunction

with the hand-lever when required; fifth, in the construction of the hand-lever and its combination with the segmental rack around which it moves; sixth, in the combination, substantially as hereinafter described, with the forward part of the beam of a plow of otherwise ordinary or suitable construction, of a hinged or pivoted arm (either adjustable or not) carrying the forward roller, and a slotted branch arm connected with the roller-arm and the beam, and curved concentrically with the center of motion of the roller-arm, whereby said roller-arm may be swung up or down so as to raise or lower the roller, and then be held in the desired position by means of the set-screw or equivalent device which fits in the slotted branch arm, and connects the same with the plow-beam.

The nature of my invention will be readily understood by reference to the drawings, in which—

Figure 1 is a plan view of a sulky-plow made in accordance with my invention. Fig. 2 is a side elevation of the same with one of the wheels removed. Figs. 3 and 4 are views of different arrangements of the device for carrying and adjusting the forward roller last above mentioned.

The attachment of the plow to the sulky-frame A is accomplished simply yet effectively by means of two arms, a, hinged to the axle at b, and having their ends which are to hold the plow-beam B united together so as to form in some sort a box which fits over the beam, and is held to the same by means of a pin, c, which passes through a slot, d, in the beam. These arms stiffen and brace the plow, and give it strength just where it is needed. They are also employed to raise or lower the plow, and to this end are connected with a suitable system of levers, e, which are actuated by the hand-lever f. In connection with this hand-lever, a lever, i, located in convenient proximity to the driver's foot, and connected with the plow by a chain or equivalent device, k, may be employed, if at any time it is found convenient or necessary to apply more power than the hand-lever can furnish. The front end of the plow-beam is connected with the whiffletree C by means of a draft-chain, g, or its equivalent.

The whiffletree itself is secured in place by

a bolt passing through a slot, *h*, in the pole of the sulky-frame. The object of the slots *h* and *d* in the pole and plow-beam is, as explained in my patent hereinbefore referred to, to allow the necessary longitudinal play of the plow while being raised or lowered, and at other times when needed. It will be noticed that the draft is direct upon the plow, and that the sulky-frame is therefore subject to no undue strain.

In order to regulate the depth of furrow I employ a stiff or rigid gage-bar, *l*, which is pivoted to the plow-beam and passes up through the sulky-frame, where it is held by means of a pin passing through one of the series of gage-holes in the bar. By raising or lowering this bar, the depth of penetration of the plow can be regulated at pleasure. As the bar is stiff and unyielding, it forces the point of the plow, just as soon as the machine moves forward, to instantly bite or enter the earth. It will be seen, also, that by reason of the slots *h* and *d*, the plow, no matter what the gage may happen to be, can be lifted or depressed by means of the hand-lever, without altering the gage, for the gage-bar, being in effect pivoted at both ends, allows the free movement of the beam.

In order to determine and fix the hand-lever in any required position, I employ with it a catch-bar, *m*, which is capable of sliding up and down in a yoke, *n*, attached to the lever. The upper part of bar *m* is pivoted to a bell-crank lever, *o*, the longer arm of which constitutes, in conjunction with the end of the lever, the handle by which the device is operated. The lever *o* in its normal position is thrown out from the lever *f* by means of a spring, *p*, so as to depress the bar *m*, and cause its end to enter one of the recesses in the segmental rack *r*. The end of the bar *m* is also forked, so as not only to enter the recess in the rack but to extend down on each side of the same, and thus to steady the hand-lever and prevent any lateral motion. It is needless to say that the rack is curved in the arc of a circle which has the pivot of the hand-lever for its center.

In using the hand-lever the operator takes it by the handle, and, naturally pressing the longer arm of the lever *o* toward the hand-lever, thereby draws up the bar *m*, disengages it from the rack, and leaves the hand-lever free to be moved to any point desired.

By means of the devices hereinbefore described the depth of furrow can be regulated, and the plow can be raised entirely from the ground while going to or returning from work. It sometimes happens, however, that the plow is removed from the sulky and has applied to it the ordinary beam and handles, and in such case it becomes necessary to provide means for gaging the plow, or lifting it entirely from the ground. For this purpose I employ a very efficient device. (Shown in Figs. 3 and 4.) It consists of an arm, *s*, which is pivoted to

the forward part of the plow-beam *B*, and carries at its lower end the roller *t*. Between the pivot and the roller is arranged a branch arm, *v*, which is curved so as to describe a portion of a circle of which the pivoted point of the arm *s* is the center, and has formed in it a slot, *w*, or its equivalent, through which passes a set-screw, *x*, which enters the beam. By loosening the set-screw the arm *s* may be swung up or down so as to set the roller at any gage desired, after which the screw is tightened and the whole device thereby is fixed firmly in place. The arm should be of such length that when it is in a perpendicular position the roller should come at least an inch below the point of the plow. In Fig. 4 the arm *s* and branch arm *v* are formed in one piece. In Fig. 3 the branch arm is fastened to both roller-arm and plow-beam in an adjustable manner, while the roller-arm is also adjustable up and down. Either device will operate well, though that shown in Fig. 3 is adapted more especially to be used with plows of varying sizes. The manner in which the device shown in this figure is operated is as follows:

First mark the height of plow and determine to what height the roller-arm must be adjusted to bring the roller, when held perpendicularly, at least one inch below the level of the plow-point. Then see how far forward on the plow-beam the branch arm will reach from the pivoted point of the roller-arm, and, having determined this, fix one end of the branch arm at this point on the plow-beam, and fix the other end on the lower part of the roller-arm at a point equidistant with the point selected on the plow-beam from the pivoted point of the roller-arm. Thus, no matter what may be the length of the roller-arm, the branch arm can always be correspondingly adjusted, and the same device therefore is adapted to be used on plows of varying sizes.

The operation of the device shown in Fig. 4 will be understood without explanation. It will be seen, however, that though the two devices differ slightly in construction, they, however, possess in common the essential feature of the roller-arm combined with a curved branch arm, by the adjustment of which the position of the roller is determined.

Having described my invention, and the manner in which the same is or may be carried into effect, what I claim, and desire to secure by Letters Patent, is—

1. The combination, substantially as herein described, with the hinged plow-beam and sulky-frame, of a stiff or rigid gage-bar to regulate the depth of furrow, and to cause the plow-point to bite or enter the ground at the instant the machine is moved forward.

2. The combination, with the plow-beam, of arms hinged to the sulky-frame and connected with the beam and with the lever for elevating the same as herein described, so that said

arms shall serve both to stiffen or brace, and, in connection with the lever, to raise or depress, the plow.

3. The combination, with the slotted plow-beam and whiffletree held in a slot in the sulky-frame or pole, and connected with the beam by a draft-chain or equivalent device, of the hinged bracing-arms, the lever for actuating the same, and the rigid or stiff gage-bar, substantially as and for the purposes set forth.

4. The combination and arrangement, substantially as herein specified, of the plow-beam with the hand-lever for raising or lowering the same, and an auxiliary foot-lever, independent of and having no connection with the hand-lever, but connected with the beam and adapted to act in conjunction with the hand-lever when required.

5. The combination, with the hand-lever and segmental rack, of the sliding catch-bar and

device for operating the same, said bar being held to the lever and forked so as to straddle the rack, as and for the purposes shown and set forth.

6. The combination, with the forward part of the beam of a plow of otherwise ordinary or suitable construction, of a pendent arm carrying the roller, and pivoted or hinged to the plow-beam, and a curved and slotted branch arm connected with both the plow-beam and the roller-arm, in the manner and for the purposes substantially as described.

In testimony whereof I have signed my name to this specification before two subscribing witnesses.

LEAVITT HUNT.
